UNITED STATES PATENT OFFICE

RALPH L. BROWN, OF NEWARK, NEW JERSEY, ASSIGNOR TO BRANDES LABORATORIES, INC., OF NEWARK, NEW JERSEY, A CORPORATION OF NEW JERSEY

ELECTROMAGNETIC SOUND REPRODUCER

Application filed December 11, 1926. Serial No. 154,256.

My invention relates broadly to electromagnetic sound reproducers and more particularly to an electromagnetic sound reproducer having a sound reproducing diaphragm of a free edge cone construction.

One of the objects of my invention is to provide an electromagnetic sound reproducer having a free edge sound reproducing diaphragm which is supported at its apex from 10 a member which protrudes from the electromagnetic driver with means for steadyng the cone shaped diaphragm at a plurality of points throughout the area of the cone shaped diaphragm.

Another object of my invention is to provide a free edge cone shaped sound reproducing diaphragm construction in which a plurality of flexible centering members are distributed throughout the area of the concave side of the sound reproducing diaphragm for aligning the diaphragm with respect to the electromagnetic driver, the driver serving to support the diaphragm wholly from the apex thereof.

Still another object of my invention is to provide a construction of centering devices which may be secured to the concave side of the cone shaped sound reproducing diaphragm at points distributed throughout the 30 area thereof, the centering devices having a flexible membrane thereon by which movement may be freely imparted to the cone shaped sound reproducing diaphragm while the diaphragm is centered at all times in a selected position.

My invention will be more fully understood from the specification hereinafter following by reference to the accompanying drawings wherein:

Figure 1 is a vertical cross-sectional view of the sound reproducer of my invention; Fig. 2 is a cross-sectional view taken laterally through the electromagnetic sound reproducer of my invention; Fig. 3 is a detailed cross-sectional view showing the construction of one of the centering devices of my invention with the cone shaped sound reproducing diaphragm flexed to its extreme left hand position; and Fig. 4 is a detailed cross-sec-

tional view of the centering device flexed to its extreme right hand position.

My invention is directed to that class of electromagnetic sound reproducers which employ a free edge cone shaped sound reproducing diaphragm. The cone shaped diaphragm is supported from its apex to which vibrations are imparted from an electromagnetic driver. The diaphragm is centered with respect to the electromagnetic 55 driver by a plurality of centering devices positioned on the concave side of the cone shaped sound reproducing diaphragm and which connect with brace members extending from the housing 1 which encloses the electromagnetic driver. The centering devices are each capable of being flexed from one side to another in accordance with the movement of the cone shaped sound reproducing diaphragm. I provide a protecting 60 housing around the cone shaped diaphragm which serves as a sound reflector for the distribution of sound from the loud speaker in many different directions.

Referring to the drawings in more detail 65 reference character 1 designates the base member for the loud speaker with an upwardly protruding member 2 carried thereby on which is supported the housing 3 for enclosing the electromagnetic driving mechanism. The housing 3 is screw threaded to receive the rotatable plate member 4, which carries the electromagnets of the electromagnetic operating mechanism. The plate member 4 is provided with teeth at its periphery as 70 represented at 5 which are engaged by pinion 6 rotated by shaft 7 for moving the plate member 4 to a selected position. The shaft 7 is provided with an actuating control knob 8 which projects outside of the limits of the 75 housing of the electromagnetic sound reproducer. A bearing 9 carried by depending member 10 secured adjacent the annular flange 11 of the sound reflector 12 is provided for supporting the rotatable shaft 7. Lug 80 members 14, 15 and 16 are formed on the housing 3 and to these lug members I connect brace members 17, 18 and 19 which connect at their outer ends to the centering devices 100 20, 21 and 22 which are secured to the concave

side of the sound reproducing diaphragm 23. Each of the centering devices comprise circular members. I have illustrated the construction of the centering devices in detail in Figs. 3 and 4 as consisting of a cylindrical portion 24 with radially directed out-turned lug portions 25 which are secured to the rear of the sound reproducing diaphragm 23. The end of the cylindrical portion 24 is turned inwardly as represented at 26. Closing the cylindrical opening in the end 26 I provide a flexible sheet or resilient gasket member 27. This flexible sheet or resilient gasket member is secured at its center by bolt member 28 to the end of the brace members. Each of the centering devices are similarly constructed and permit free movement of the sound reproducing diaphragm 23 under action of the electromagnetic driver in housing 3 through connecting rod 29 secured at its apex by means of screw chuck device 30. The sound reproducing diaphragm 23 has its free peripheral edge strengthened by a suitable bead 31. The beaded edge of the sound reproducing diaphragm extends within the protection offered by the annular closure member 32 which connects at its periphery through bolt members 33 with the sound reflector 12. The sound reflector 12 is open at one side thereof as represented at 34, the opening being closed by means of ornamental grille 35. By this arrangement sound emanates from both the front and rear of the cone shaped diaphragm 23 and is partially reflected by the reflecting surface formed by the annular member 32 and by the reflecting surface 12, the conjoint action of which tends to substantially increase the volume of the reproduced sound.

The particular embodiment of my invention as described herein has been found to be very practical in construction and desirable in operation although it should be understood that modifications may be made and that I intend no limitations upon my invention other than are imposed by the scope of the appended claims.

What I claim as new and desire to secure by Letters Patent of the United States is as follows:

50. 1. A sound reproducer comprising a supporting member, an actuating mechanism carried by said supporting member, a free edge cone shaped sound reproducing diaphragm driven by said actuating mechanism and connections between said supporting member and three equi-distant points on the concave side of said cone shaped sound reproducing diaphragm remote from the peripheral edge of the diaphragm in the direction of the apex for centering said diaphragm with respect to said actuating mechanism.

60. 2. A sound reproducer comprising a supporting member, an actuating mechanism carried by said supporting member, a free edge cone shaped sound reproducing dia-

phragm operated by said actuating mechanism, and connections extending from said supporting member to a plurality of equi-distant points on the concave side of said cone shaped sound reproducing diaphragm remote from the peripheral edge of the diaphragm in the direction of the apex for centering said cone shaped diaphragm with respect to said actuating mechanism. 70

3. A sound reproducer comprising a supporting member, an actuating mechanism carried by said supporting member, a free edge cone shaped sound reproducing diaphragm driven by said actuating mechanism, and means extending between said supporting member, and a plurality of points around the concave side of said cone shaped sound reproducing diaphragm remote from the edge of the diaphragm in the direction of the apex and flexibly connected with said diaphragm for centering said diaphragm with respect to said actuating mechanism. 75

4. A sound reproducer comprising a supporting member, an actuating mechanism carried by said supporting member, a free edge cone shaped sound reproducing diaphragm operated by said mechanism, a plurality of flexible connectors secured to the concave side of said conical-shaped sound reproducing diaphragm, in positions remote from the peripheral edge thereof, and connections between said connectors and said supporting member for centering said sound reproducing diaphragm with respect to said actuating mechanism. 80

5. A sound reproducer comprising a supporting member, an actuating mechanism carried by said supporting member, a free edge cone shaped sound reproducing diaphragm operated by said actuating mechanism, a plurality of connecting members secured at a plurality of points about the concave surface of said sound reproducing diaphragm, each of said connecting members including a resilient gasket device extending in a plane substantially parallel to the concave surface of the diaphragm, and a connection between the gasket devices of each of said members and said supporting member whereby said sound reproducing diaphragm may be centered with respect to said actuating mechanism. 100

6. A sound reproducer comprising a supporting member, an actuating mechanism carried by said supporting member, a free edge cone shaped sound reproducing diaphragm operated by said actuating mechanism, a plurality of cylindrical members secured to the concave surface of said sound reproducing diaphragm, a flexible membrane closing one side of said cylindrical members, and connections between said flexible membrane and said supporting member for centering said diaphragm with respect to said actuating mechanism. 105

7. A sound reproducer comprising a sup- 110

130

porting member, an actuating mechanism carried by said supporting member, a free edge cone shaped sound reproducing diaphragm actuated by said actuating mechanism, means centering said diaphragm from points inside 5 the concave surface thereof and remote from the peripheral edge of the cone and a sound reflector positioned adjacent the peripheral edge of said sound reproducing diaphragm and centrally apertured adjacent the concave 10 side of said sound reproducing diaphragm whereby sound is radiated from both sides of said sound reproducing diaphragm.

8. In a sound reproducer, a cone shaped sound reproducing diaphragm, an actuating 15 driver, a housing enclosing said actuating driver, said driver having means for supporting said cone shaped sound reproducing diaphragm from the apex thereof and imparting vibratory motion thereto, and centering devices each comprising a flexible member secured in parallel spaced relation to one side 20 of said diaphragm and a flexible connection between each of said members and said housing.

25 In testimony whereof I affix my signature.
